UNITED STATES PATENT OFFICE.

ARTHUR J. BRIGGS, OF SYRACUSE, NEW YORK, ASSIGNOR TO REMINGTON TYPEWRITER COMPANY, OF ILION, NEW YORK, A CORPORATION OF NEW YORK.

TYPE-WRITING MACHINE.

1,214,891.

Specification of Letters Patent.

Patented Feb. 6, 1917.

Application filed November 24, 1913. Serial No. 502,785.

To all whom it may concern:

Be it known that I, ARTHUR J. BRIGGS, citizen of the United States, and resident of Syracuse, in the county of Onondaga and State of New York, have invented certain new and useful Improvements in Type-Writing Machines, of which the following is a specification.

My invention relates to typewriting machines and more particularly to ribbon feed mechanism for such machines.

The main object of my invention, generally stated, is to provide ribbon feed mechanism which is simple in construction, efficient in use and which may be manufactured at small cost.

To the above and other ends which will hereinafter appear, my invention consists in the features of construction, arrangements of parts and combinations of devices set forth in the following description and particularly pointed out in the appended claims.

In the accompanying drawings wherein like reference characters indicate corresponding parts in the various views,

Figure 1 is an enlarged, detail, fragmentary, vertical, fore and aft sectional view of one form of typewriting machine embodying my invention, sufficient number of parts of the machine being shown to illustrate my invention in its embodiment therein.

Fig. 2 is a detail, fragmentary, sectional view taken on the line $x-x$ of Fig. 3 and looking in the direction of the arrow at said line.

Fig. 3 is an enlarged, fragmentary, top plan view of the ribbon feed and reversing mechanism with parts omitted and parts broken and sectioned away.

Fig. 4 is a fragmentary, front elevation of the ribbon vibrator and some of the associated parts.

Fig. 5 is an enlarged, detail, fragmentary, sectional view of the right-hand ribbon spool and some of the associated parts, the section being taken on the line $y-y$ of Fig. 3 and looking in the direction of the arrow at said line.

Fig. 6 is an enlarged, detail, fragmentary,

front elevation with parts in section of a portion of the ribbon feed mechanism.

I have shown my invention embodied in the present instance in a front-strike typewriting machine of the character disclosed in my applications, Serial Nos. 782,859; 786,107; 786,108; 790,583; 791,734 and 795,667 and some of the features shown herein are claimed in certain of said previously filed applications. It should be understood, however, that my present invention may be embodied in other styles of typewriting machines.

In the present construction segmentally arranged type bars 1 are pivoted at 2 to 65 swing upwardly and rearwardly and to strike against the front face of a platen 3. Each type bar is pivoted to a hanger 4 secured by screws 5 to a type bar segment 6 connected at its ends to side plates 7 of the 70 frame of the machine. Each type bar is connected through a pull link 8 with suitable key controlled actuating devices, such, for example, as those illustrated in my application, Serial No. 795,667.

A segmental universal bar 9 is so arranged that the front edge 10 thereof is engaged by the front edge of each type bar, near the heel of the latter, as the type bar moves to the printing position under the depression 80 of a printing key. The universal bar being engaged by the type bars in the manner described, is moved from the normal position shown in Fig. 1 rearwardly to effect an actuation of the escapement mechanism (not 85 shown) and the ribbon mechanism, as will hereinafter more clearly appear.

The platen 3 is carried by a platen shaft 11 which is received in bearing openings in end plates 12 of the carriage, said end plates 90 extending upwardly from a traverse bar 13 mounted for movement from side to side of the machine. Thus the traverse bar is provided with oppositely disposed race-ways 14 which receive anti-friction balls 15 and 16. 95 The balls 16 are also received in a race-way 17 formed in a shift bar, rail or frame 18. This bar 18 has a plate 19 secured thereto by screws 20, the plate being grooved to form a raceway 21 for the reception of anti-

75

100

friction balls 15. In this manner the carriage comprising the traverse bar 13 and end plates 12 united by a tie rod 22 is supported to travel from side to side of the machine on the shift rail 18.

5 The construction of the carriage and the manner of mounting the same is claimed in my application, Serial No. 782,859, hereinbefore referred to.

10 The shift rail or bar 18 is mounted on and guided by parallel shift links 23 each pivoted at its forward end, as at 24, to the shift rail and pivoted at its rear end, as at 25, to a side plate of the machine. A second 15 set of parallel links 26 is also connected to the shift rail. Thus each of these links is pivoted at its forward end, as at 27, to a depending arm 28 on the shift rail 18, whereas the rear end portion of each link is pivoted 20 at 29 to the frame of the machine. The links 26 are extended rearwardly beyond their pivots 29 to form arms 30 which are united by a cross bar or rod 31. The shift rail and the parts carried thereby are thus 25 mounted for ease shifting movement under the control of suitable ease shifting mechanism, such for example, as that disclosed in my application, Serial No. 791,734, hereinbefore referred to and in which application 30 the case shift mechanism is claimed.

The universal bar 9 has fixedly connected therewith a centrally disposed rearwardly extending arm 32 formed at the rear portion thereof as an enlarged plate 33. This plate 35 constitutes an actuating member and has a rear contact edge 34-35 which is operative on the escapement mechanism, as disclosed in my application, Serial No. 795,667, filed Oct. 17, 1918. The universal bar and the 40 member 32-33, rigidly connected therewith, are supported on the frame of the machine for fore and aft movement. Thus parallel upright links or arms 36 are pivoted at their upper ends, as at 37, to ears 38 45 riveted at 39 to the universal bar. The lower ends of these links or arms are fixedly connected to a rock shaft 40 supported by ears 41 on a bracket plate 42, the latter being secured to the type bar segment by 50 screws 43. A rearwardly extending arm 44 on the bracket plate 42 is provided with an upwardly projecting ear 45 to which a centrally disposed link 47 is pivoted at 46. The upper end of this link is pivoted at 48 to the 55 actuating member 33. The universal bar is thus supported on the frame of the machine for movement under control of the type bars at each printing operation.

One of the links or arms 36 is extended 60 rearwardly beyond its pivotal center to form a crank arm 49 which is engaged by a suitable actuating device (not shown) under control of the space key as disclosed in my application, Serial No. 795,667.

65 A depending bracket 50 has its foot-piece

51 secured to the shift bar by screws 52. This bracket is provided with ears 53 one of which is tapped to receive a bearing screw 54. A lock nut 55 secures the bearing screw in its adjusted position. This bearing 70

screw constitutes a pivotal support with which co-operates one end of a trunnion-like pivot 56 (Fig. 6) fixed to an actuating lever 56, the other end of said trunnion-like pivot being received in a bearing opening 75

in the other ear 53 on the bracket 50. The actuating lever 56 is thus supported for ease shifting movement with the shift rail and the parts carried thereby. The lower end 80 of the actuating lever 56 is provided with a laterally projecting pin 57 which extends through an upright curved slot 58 in a depending arm 59 on the actuating member 33. An operative connection is thus effected

85 between the member 33 and the actuating lever 56 whereby a movement of the universal bar is effective to turn the actuating lever 56 on its pivot. The construction is also such as to afford a movement of the

actuating lever 56 with the shift rail independently of the member 33 and its depending arm 59. The upper end of the actuating lever 56 is pivoted at 60 to a link 61, the latter being pivoted at its forward end, as at 62, to a depending arm of an angular lever

63. The rear end of the upper arm of this lever is received in a slot or cut-out 64 in the shift rail 18 and is pivoted to the shift rail at 65. A pin 66 is fixed to the angular lever 63 and projects from opposite sides thereof and forms a pivot to which a ribbon vibrator, designated as a whole by the reference numeral 67, is connected. This vibrator is best shown in Figs. 1 and 4 from

90 which it will be seen that it extends upwardly in the rear of a type guide 68 fixed to the shift rail by screws 69. The upper portion of the type guide is bifurcated to form two arms 70 on opposite sides of a central opening 71. The upper end of each

95 arm is bent forwardly at 72 and is provided with an inclined contact face 73 which co-operates with each type block to guide it to the printing point. The ribbon vibrator 100 has two arms 74 which are spaced apart at the opening 71 in the type guide and each of these arms is provided with oppositely disposed fingers 75 which terminate before they reach contact with each other to provide a central opening 76 between them. A

105 vertically disposed slot 77 is provided between each pair of fingers 75 and the associated arm 74 which carries them, thus forming a guide slot through which the

110 ribbon 78 may extend. The ribbon vibrator 115 is also provided with lugs 79 which are bent around the inner edges of the arms 70 of the type guide and co-operate therewith to

120 guide the vibrator as the latter is moved vertically to cause the ribbon to cover and un-

125

130

135

cover the printing point. A centrally disposed depending arm 80 is formed on the vibrator and extends downwardly through an opening 81 in the type guide. The lower 5 end of this depending arm is turned at 82 around the trunnion-like pivot 66 on the angular actuating lever 63.

It will be understood that each printing operation is effective to actuate the universal bar which, through the members 33, 56, 61 and 63 is effective to move the vibrator upwardly to bring the ribbon 78 into the path of the type on the actuated type bar as it approaches the platen.

15 In order to return the universal bar and the parts operatively connected therewith to normal position, when pressure is released from the depressed printing key, I employ a contractile returning spring 83 as shown in Fig. 1. This spring is connected at its lower end to a bracket arm 84 attached to the bracket 50. The upper end of the spring is connected to a pin or arm 85 which projects rearwardly from the 25 trunnion-like pivot 56^a of the actuating lever 56. It will be understood therefore that the spring 83 not only returns the actuating lever 56 to normal position, but also returns the universal bar and ribbon vibrator which are connected therewith.

Referring more particularly to Figs. 1, 3 and 6 it will be seen that a depending arm 86 is formed on the shift bar or frame 18, and that an angular actuating lever, designated as a whole by the reference numeral 87, is pivoted at 88 on the depending arm. The substantially horizontally disposed arm 89 of the angular lever is reduced at its end, as at 90, where it is received in an 35 opening 91 in a forwardly projecting curved arm 92 formed on the actuating lever 56. Connection is thus effected between the actuating lever 56 and the angular lever 87 and each actuation of the lever 56 will effect a corresponding actuation of the lever 87.

The upright arm 93 of the angular lever is slotted at 94 to receive a headed pin 95 which projects forwardly from an actuating member or bar 96. This bar is preferably made of sheet metal and extends transversely across the machine and is mounted for endwise movement under control of the lever 87. Thus the bar 96 is provided near each end with a horizontally disposed forwardly extending ear 97 which rests on and is pivoted to an associated lever or crank arm by a pivot screw 98.

60 The levers or crank arms to which the bar 96 is connected by the screws 98 are not alike on both sides of the machine nor are the feeding means controlled by said arms alike in every particular. I will therefore first describe the crank arm 99 which is 65 located at the right-hand side of the ma-

chine and the ribbon feed devices controlled by this arm for turning the right-hand ribbon spool 100.

The ribbon spools 100 are arranged at opposite sides of the machine and are supported by the shift rail 18 and the ribbon 78 passes from one spool to the other and is threaded through the vibrator 67, as shown in Fig. 4. The actuating arm 99 is connected at its forward end to a rock 75 shaft or spindle 101, as shown in Fig. 2. The shaft 101 is flattened on opposite sides thereof at 102 and the crank arm is apertured to correspond, so as to fixedly connect the crank arm and rock shaft to move 80 together, the crank arm being held on the shaft by a screw 101^a. The shaft 101 is received in and extends through a bearing sleeve 103 which is riveted at its upper end, as indicated at 104, to the bottom member 85 105 of a two-part horizontally disposed housing or casing which incloses actuating devices for the right-hand ribbon spool. The lower member 105 of the casing is of cup-like construction, the other member 106 96 being in the nature of a cover which fits on the lower part of the casing. The upper end of the rock shaft 101 has riveted thereto a crank arm 107 contained in the casing. The free end of this arm carries an upwardly extending pin 109 which extends through a slot 108 in a lever arm 110. The arm 110 is fulcrumed at one end on a shouldered pivot screw 111 received at its lower threaded end in a tapped opening in the 100 member 105 of the casing as shown in Fig. 1. The forwardly extending free end of the lever 110 carries a pivot 112 on which an oscillatory feed device, or pawl 113 is mounted. A downwardly projecting pin 105 114 is carried by the pawl for connection with one end of a contractile spring 115. The opposite end of this spring is connected to a pin 116 which projects upwardly from the bottom of the casing. 110

From an inspection of Fig. 5 it will be seen that an upwardly projecting supporting spindle 117 is riveted at its lower end, as at 118, to the bottom of the casing section 105. This spindle is provided with a circumferential shoulder 119 against which the lower end of a sleeve, hollow spindle or shaft 120 abuts. This sleeve is adapted to surround and be supported on the spindle 117 and to turn thereon as a pivot. The sleeve 120 is 115 surrounded by a flanged collar 121 which abuts at its upper end against a circumferential shoulder 122 on the sleeve 120. The flanged portion of this collar 121 bears against the upper face of a ratchet wheel 123 to form a bearing face therefor, the sleeve 120 extending through a central opening in the ratchet wheel. The ratchet wheel and sleeve 120 are fixedly connected by riveting the lower end of the sleeve against 130

a washer 124 interposed between the lower headed end of the sleeve and the ratchet wheel. The ratchet wheel 123, the hollow spindle 120 and the collar 121 are thus fixedly connected to turn together as one part and are supported for turning movement on the spindle 117. The hollow spindle 120 is flattened on opposite sides thereof, as at 125, and is received in corresponding openings in the core of the associated ribbon spool 100, so that the shaft 120 and the ribbon spool are fixed to turn together. The upper end of the hollow shaft 120 is threaded at 126 for co-operation with a thumb nut 127 knurled on the periphery thereof and adapted to bear against the upper flange of the associated ribbon spool, as shown in Fig. 5, to bind the spool between the nut and the supporting collar 121. From an inspection of this figure it will be seen that the collar 121 extends through an opening in the upper section 106 of the two-part casing and is adapted to support the horizontally disposed ribbon spool above the cover of the casing and adjacent to but free from contact therewith. In this manner the ribbon spool may be connected to turn with the hollow spindle 120 and the ratchet wheel 123, such parts rotating around the spindle 117 while the two-part casing remains fixed. The ribbon spool may be readily detached by removing the thumb nut 127. When the spool is removed the cover section 106 may be detached to expose the devices contained in the casing. If desired, the spindle 120 and the ratchet wheel 123 connected therewith, may be lifted off the supporting spindle 117 to give access to the parts in the casing which are located beneath the ratchet wheel.

It will be understood that an endwise movement of the actuating bar 96 from left to right, as the parts are shown in Fig. 3, is effective to turn the crank arm 99 to the right, producing a corresponding movement of the crank arm 107 through the interposed rock shaft 101. This movement of the crank arm 107 is effective to move the lever 110 to the right, thereby causing a corresponding movement of the feed pawl 113. The pawl when in engagement with its associated ratchet wheel is effective, during this movement to the right, to effect a rotative movement of the ratchet wheel and the ribbon spool which is connected therewith.

The lower member 105 of the casing is secured by screws 128 to a bracket 129 fixed by screws 130 to the shift rail 18. It will be understood therefore that the two-part casing and the parts supported thereby are carried by and shiftable with the shift rail or frame 18 during the case shifting movements of the latter.

The ribbon spool 100 at the opposite or left-hand side of the machine is connected

to the associated ratchet wheel in the same manner as the right-hand spool is connected to its ratchet wheel; and the spools in both instances are supported by the two-part casing in the same manner and in each instance the casing is supported by the bracket 129 on the shift rail of the machine. Therefore the description of this mechanism at one side of the machine applies to the corresponding mechanism at the other side of the machine and the same reference numerals will be applied to the corresponding parts wherever applicable, and it will be unnecessary to specifically describe this portion of the ribbon feed mechanism for the left-hand spool. However, the actuating arm 131 for the left-hand ribbon spool and the actuating devices controlled thereby are somewhat different from the actuating arm 99 and the actuating devices controlled by this last mentioned arm. Thus the arm 131 is fixedly connected to the lower end of a rock shaft 132 which corresponds to and is mounted in the same manner as the rock shaft 101 previously described. The upper end of this rock shaft has fixedly connected thereto a crank arm 133 on the forward end of which is carried a pivot 134. A feed pawl 135 is mounted on this pivot and is adapted to co-operate with the associated ratchet wheel 123. It will be understood, however, that the pawls 135 and 113 move in opposite directions from the normal position and that this movement of the pawls is effected by an endwise movement of the actuating bar 96 in one direction, or from left to right. In other words, as the actuating bar 96 moves to the right from the normal position shown in Fig. 3, the pawl 113 will be moved to the right, whereas the pawl 135 will be moved to the left. This movement of the pawls in opposite directions is effective to positively turn one or the other of the ribbon spools, depending on which of the ratchet wheels is engaged by its associated pawl, as will hereinafter more clearly appear. It should be understood that a movement of the actuating bar 96 to the right from the normal position, shown in Fig. 3, is positively effected by the depression of a printing key, and while the associated type bar is moving toward the printing position. It will be understood therefore that whichever spool is the driven spool, whether the right-hand or left-hand spool, it will be positively turned at each printing operation, and the feed movement of the ribbon in either instance is not dependent on the returning spring 83 by which the bar 96 and the parts connected therewith are returned to normal position.

In order to prevent a backward movement of the actuated ratchet wheel and the spool connected therewith during the return movement of the pawl 113 or 135 which coacts therewith, I have provided a locking pawl 130

136 associated with each ratchet wheel. Each of these pawls is mounted on a pivot 137 which projects upwardly from the associated casing member 105. A contractile spring 138 is connected at one end to a depending pin 139 on the associated pawl 136 and at its opposite end to a pin 140 on the casing. Each pawl 136 is therefore forced toward its associated ratchet wheel and into engagement with the teeth thereon to hold the ratchet wheel against backward turning movement during the return movement of the associated feed pawl.

I have provided automatically operating controlling or reversing means for maintaining the pawls of one ribbon spool out of engagement with the associated ratchet wheel when the pawls of the other ribbon spool are in engagement therewith, as shown in Fig. 3. The construction is such that an automatic operation of the reversing means will take place when the ribbon is about exhausted from one of the ribbon spools so as to throw the ribbon feed devices of the exhausted spool into operation and to simultaneously render the feed devices for the other spool ineffective. In Fig. 3 the parts are shown as they are disposed when the ribbon is about exhausted from the left-hand ribbon spool and just before an actuation of the reversing devices is effected. A curved arm 141 is contained within the right-hand casing and one end of this arm is fixedly secured to the upper end of a rock shaft 142 which, as shown in Fig. 2, is mounted to turn in a sleeve 143 riveted at 144 to the casing section 105. The lower end of this shaft is flattened at 145 and a corresponding opening is formed in one end of an arm 146 which extends rearwardly from the lower end of the shaft and beneath the associated casing, the arm being held in place on its shaft by a threaded screw 142. This arm is pivotally connected at its rear end to one end of a rod 147 which extends transversely across the machine and is contained in a recess formed in the shift bar 18. The arm 141 has an extension 148 which projects through a slot or opening 149 in the housing and carries an upwardly extending ribbon guide 150 which forms part of the arm 141. This guide 150 is slotted at 151 for free passage therethrough of the ribbon as it passes from its associated ribbon spool across the machine to the opposite ribbon spool. The arm 141 is also formed with dwells, contact edges or controlling members 152, 153, the former of which is adapted to coöperate with the retaining pawl 136 and the latter of which is adapted to coöperate with the feed pawl 113. When the parts are disposed as represented in Fig. 3 the contact portions or dwells 152, 153 will be positioned so that they are out of coöperative relation with the pawls 113 and 136, so that the pawls may

be forced and maintained in engagement with the associated ratchet wheel by the springs which are connected to said pawls. When, however, the arm 141 is shifted to the operative position the contact portions 152 and 153 thereon are brought into engagement with their respective pawls, forcing and maintaining the latter out of engagement with the ratchet wheel 123 with which they coact as indicated at the left-hand side 75 of Fig. 3.

The opposite end of the rod 147 is connected to an arm 154 which corresponds to the arm 146. This arm 154 is fixedly connected to a rock shaft 155 mounted in the same manner as the rock shaft 142, previously described. This shaft 155 is also connected with an arm 156 which corresponds to the arm 141. Contacts or dwells 157, 158 are formed on an extension of the arm 156 85 to co-act with the pawls 135 and 136, respectively, of the left-hand ribbon spool ratchet wheel. This arm 156 is also provided with an extension 159 which extends through a slot 160 in the casing and carries 90 a slotted guide 161 through which the ribbon 78 passes.

The ribbon near each end thereof is provided with a contact device, each designated as a whole by the reference numeral 162. 95 Each contact device preferably consists of a rivet 163 which passes through the central openings in two registering washers 164 and through an opening in the ribbon. The washers are arranged on opposite sides of 100 the ribbon and are fixed to the ribbon by the rivet. Each of these contact devices is of such a size that it cannot pass through the opening in its associated ribbon guide, as indicated in Fig. 3. It will be understood 105 from an inspection of this figure that the ribbon is about exhausted from the left-hand spool. As the ribbon continues to be wound on the right-hand spool the contact device 162 near the left-hand end of the ribbon engages the ribbon guide 161 and the pull of the ribbon turns the arm 156 on the pivotal center of the rock shaft 155. This is effective to move the contacts 157 and 158 to the right and nearer the pivotal axis of the associated ratchet wheel so that they no longer coact with their respective pawls 135 and 136, and these pawls are thus enabled to engage the associated ratchet wheel. A movement of the actuating bar 96 to the right, at this time, is effective to turn the left-hand ratchet wheel and the ribbon spool connected therewith. The shifting movement of the arm 156 just described is effective, through the arms 154 and 146 and the interposed connecting link or rod 147, to shift the arm 141 of the opposite spool from the position shown in Fig. 3 to a position corresponding to that of the arm 156 shown in that figure. The effect therefore is to bring the contact 110 115 120 125 130 135 140 145 150 155 160 165 170 175 180 185 190 195 200 205 210 215 220 225 230 235 240 245 250 255 260 265 270 275 280 285 290 295 300 9845 9850 9855 9860 9865 9870 9875 9880 9885 9890 9895 9900 9905 9910 9915 9920 9925 9930 9935 9940 9945 9950 9955 9960 9965 9970 9975 9980 9985 9990 9995 9999

faces 152 and 153 into engagement with the pawls 136 and 113, respectively, of the right-hand spool to move said pawls to and maintain them in the disengaged position so that 5 an operation of the actuating bar 96 at this time will be ineffective to turn the right-hand ribbon spool through the ribbon feed or actuating devices therefor.

When the ribbon is fully wound on the 10 left-hand spool, and is about exhausted from the right-hand spool, the contact device 162 near the right-hand end of the ribbon will engage the ribbon guide 150 and shift it to the position shown in Fig. 3. This again 15 renders the right-hand actuating pawl 113 and the companion holding pawl 136 effective to coöperate with the associated ratchet wheel, and the ribbon will be wound on the right-hand instead of on the left-hand spool. 20 This same shifting movement of the arm 141 is effective through the intermediate connections to disengage the pawls 135 and 136 for the left-hand spool from the associated ratchet wheel.

25 From the foregoing description it will be understood that a depression of the printing key is effective to move the associated type bar to the printing position, and that during this movement the type bar will engage 30 the universal bar 9 and move it rearwardly. The effect of this movement of the universal bar is to move the upper end of the actuating lever 56 forwardly in order to operate the vibrator and interpose the ribbon in the 35 path of the approaching type bar. A forward movement of the arm 92 on the lever 56 is also effected at this time and said movement is operative to depress the arm 89 of the angular lever 87, thereby moving the upper 40 right arm 93 of said angular lever to the right and transmitting an endwise movement of the bar 96 to the right from the position shown in Fig. 3. This movement of the actuating bar 96 is effected during the 45 depression of the key and a positive movement of the active ribbon spool will be effected. During the return movement of the parts under the action of the returning spring 83 the bar 96 will move from right to left, and at this time the actuating pawl of the active ribbon spool will glide over the teeth of its associated ratchet wheel irrespective of which spool is being driven.

50 In order to insure a complete and quick movement of the reversing devices at each actuation thereof, and in order to prevent an accidental displacement of said devices from the position to which they are shifted, I have provided a spring detent 165 which is formed with a foot-piece 166 fixed to the lower section of the left-hand casing by a screw 167. The foot-piece is also provided with a downwardly extending projection 168 which extends through an opening 169 in 55 the bottom of the casing, thus preventing

the foot-piece from turning on the screw 167. The spring is formed near the free end thereof with a detent or engaging portion 170 having oppositely inclined faces which are adapted to engage an anti-friction roller 171 carried by a pivot 172 which projects downwardly from the arm 156. The inclined face of the detent which is engaged by the roller depends on the position to which the arm 156 is shifted, the pressure 70 of the detent being exerted against one side or the other of the roller as the roller passes to one side or the other of the apex formed at the junction between the two inclined faces of the detent. It should be understood, of course, that the detent is operative to insure a completion of the movement of the reversing devices for both spools through the intermediate connections formed between said reversing devices. 85

From the foregoing description it will be understood that the ribbon feed devices, reversing devices, the ribbon spools, the two-part casings, the actuating bar 96, the ribbon vibrator and actuating lever 63, link 61, lever 56 and angular lever 87 are all carried by the shift rail and are shiftable with the platen in the case shifting movements of the latter, so that operative relation may be maintained between these various devices 95 irrespective of the position to which the platen may be shifted.

It will also be understood that the ribbon feed and ribbon reversing mechanisms are simple in construction, effective in use and 100 may be manufactured at small cost, most of the parts being stamped up or made from sheet metal. Moreover, it will be understood that the construction is such that the parts 105 may be readily assembled and that access may be readily gained thereto without dismantling other parts of the machine. Furthermore, the ribbon feed and reversing mechanisms may be assembled outside of and introduced as a unit into the machine. 110

While I have shown and described with considerable particularity one form of construction embodying my invention, it should be understood that various changes may be made without departing from the spirit and scope of my invention and that certain features thereof may be employed without others. 115

What I claim as new and desire to secure by Letters Patent, is:—

1. In a typewriting machine, the combination of a covered casing, a ribbon spool outside of but adjacent to said casing, an actuating pawl contained within said casing, a ratchet wheel contained within said casing and with which said pawl co-acts, means for detachably connecting the ribbon spool to said ratchet wheel, a reversing device in said casing and operative to control the engagement between said pawl and 125 130 135

ratchet-wheel, a ribbon, and means whereby the pull on the ribbon is rendered effective to shift said reversing device.

2. In a typewriting machine, the combination of a covered casing, a ribbon spool outside of but adjacent to said casing, an actuating pawl contained within said casing, a ratchet wheel contained within said casing and with which said pawl co-acts, 10 means for detachably connecting the ribbon spool to said ratchet wheel, a reversing device in said casing and operative to control the engagement between said pawl and ratchet wheel, said reversing device being 15 provided with a ribbon guide, a ribbon, and a contact device carried by said ribbon and operative on the ribbon guide to shift the reversing device.

3. In a typewriting machine, the combination of a shiftable platen, a pair of casings arranged at opposite sides of the machine and shiftable with the platen and each having a detachable cover, a movable arm contained in each of said casings, a pawl 25 carried by each of said arms, a ratchet wheel contained in each casing and with which the associated pawl co-acts, a ribbon spool arranged outside of each casing and adjacent to the cover thereof, and means for 30 communicating movement from each of said ratchet wheels to the associated ribbon spool.

4. In a typewriting machine, the combination of a shiftable platen, a pair of casings arranged at opposite sides of the machine and shiftable with the platen and each having a detachable cover, a movable arm contained in each of said casings, a pawl carried by each of said arms, a ratchet wheel contained in each casing and with which 10 the associated pawl co-acts, a ribbon spool arranged outside of each casing and adjacent to the cover thereof, means for communicating movement from each of said ratchet wheels to the associated ribbon spool, 15 and a reversing device in each casing and cooperative with the pawl therein to control its engagement with the associated ratchet wheel.

5. In a typewriting machine, the combination of ribbon spools; and ribbon feed mechanism comprising a bar which is actuated at ratchet wheels to the associated ribbon spool, actuating devices which are moved in opposite directions by a movement of the bar in 55 one direction.

6. In a typewriting machine, the combination of ribbon spools; ribbon feed mechanism comprising a bar which is actuated at each printing operation, and ribbon-spool 60 actuating devices which are moved in opposite directions by a movement of the bar in one direction; and reversing means for rendering one of said oppositely movable actuating devices operative to positively turn one ribbon spool and to render the other of

said actuating-devices inoperative to turn the other spool.

7. In a typewriting machine, the combination of ribbon spools; and ribbon feed mechanism comprising a bar which is actuated at each printing operation, a ratchet wheel for each ribbon spool, a pawl for each ratchet wheel, and actuating means controlled by a movement of said bar in one direction for moving said pawls in opposite directions. 75

8. In a typewriting machine, the combination of ribbon spools; ribbon feed mechanism comprising a bar which is actuated at each printing operation, a ratchet wheel for each ribbon spool, a pawl for each ratchet 80 wheel, and actuating means controlled by a movement of said bar in one direction for moving said pawls in opposite directions; and reversing means for rendering one of said pawls inoperative on its ratchet wheel 85 when the other of said pawls is rendered operative on its ratchet wheel.

9. In a typewriting machine, the combination of ribbon spools; ribbon feed mechanism comprising a bar which is actuated at each printing operation, a ratchet wheel for each ribbon spool, a pawl for each ratchet wheel, and actuating means controlled by a movement of said bar in one direction for moving said pawls in opposite directions; reversing means for rendering one of said pawls inoperative on its ratchet wheel when the other of said pawls is rendered operative on its ratchet wheel; and automatically operating means controlled by the pull of the 95 ribbon for shifting said reversing means when the ribbon is about exhausted from either ribbon spool. 100

10. In a typewriting machine, the combination of a carriage, a bar by which said carriage is wholly supported, brackets secured to said bar, casings secured to said brackets, ribbon feed and reversing devices contained within said casings, parts of said ribbon feed devices extending outside the casings, ribbon spools carried by the casings and turned by said ribbon feed devices, a longitudinally movable actuating bar which extends transversely of the machine and is wholly supported by said parts of the ribbon feed devices which extend outside the casings, and means for effecting a longitudinal movement of said bar at each printing operation. 110

11. In a typewriting machine, the combination of a carriage, a bar by which said carriage is wholly supported, brackets secured to said bar, casings secured to said brackets, ribbon feed devices contained within and supported by said casings and having arms that extend outside thereof, ribbon reversing devices contained within and supported by said casings and having arms that extend outside thereof, ribbon spools carried by said casings and turned by said rib- 115 120 125 130

bon feed devices; a rod which connects said arms of the reversing devices; a longitudinally movable actuating rod or bar which connects and actuates said arms of the feed devices, and means for effecting a longitudinal movement of said actuating bar at each printing operation.

12. In a typewriting machine, the combination of a carriage, a bar by which said carriage is wholly supported, brackets secured to said bar, casings secured to said brackets, ribbon feed and reversing devices contained within said casings, parts of said ribbon feed devices extending outside the casings, ribbon spools carried by the casings and turned by said ribbon feed devices, means controlled by the pull of the ribbon for actuating said reversing devices, a longitudinally movable actuating bar which 20 extends transversely of the machine and is wholly supported by said parts of the ribbon feed devices which extend outside the casings, and means for effecting a longitudinal movement of said bar at each printing operation.

13. In a typewriting machine, the combination of a carriage, a bar by which said carriage is wholly supported, brackets secured to said bar, casings secured to said brackets, ribbon feed devices contained within and supported by said casings and having arms 30 that extend outside thereof, ribbon spools carried by said casings and turned by said ribbon feed devices, a rod which connects said arms of the reversing devices, means controlled by the pull of the ribbon for actuating said reversing devices, a longitudinally movable actuating rod or bar which connects said arms of the feed devices, and means for effecting a longitudinal movement of said actuating bar at each printing 45 operation.

14. In a typewriting machine, the combination of a carriage; a supporting bar for said carriage; casings secured to said bar; ribbon spools supported by said casings; 50 and ribbon feed devices carried by said casings and operative to turn said ribbon spools, said ribbon feed devices for each spool comprising an arm contained within the associated casing, a rock shaft which extends through the associated casing from the inside to the outside thereof and carries said arm at the inner end thereof, a bearing sleeve fixed to the casing and through which said shaft extends, and an actuating arm 55 fixed to the outer end of said rock shaft, and means for operating said actuating arm at each printing operation.

15. In a typewriting machine, the combination of a carriage; a supporting bar for 60 said carriage; casings secured to said bar;

ribbon spools supported by said casings; ribbon feed devices carried by said casings and operative to turn said spools; and ribbon reversing mechanism carried by said casings and comprising for each spool a reversing device contained within the associated casing, a rock shaft extending through the casing and having said reversing device connected at the inner end thereof, a bearing sleeve fixed to the casing and through which said rock shaft extends, and an arm outside of the casing and connected to the outer end of said rock shaft.

16. In a typewriting machine, the combination of a carriage; a supporting bar for 80 said carriage; casings secured to said bar; ribbon spools supported by said casings; ribbon feed devices carried by said casings and operative to turn said spools; and ribbon reversing mechanism carried by said 85 casings and comprising for each spool a reversing device contained within the associated casing, a rock shaft extending through the casing and having said reversing device connected at the inner end thereof, a bearing sleeve fixed to the casing and through which said rock shaft extends, an arm outside of the casing and connected to the outer end of said rock shaft, a rod which connects said last mentioned arm with the 90 corresponding arm for the other ribbon spool, and means controlled by the pull of the ribbon for actuating said reversing devices.

17. In a typewriting machine, the combination of two ribbon spools, a ratchet wheel for each spool, a driving pawl for each ratchet wheel, a crank arm carrying one of said pawls, a lever fulcrumed at one end and carrying at the other end thereof the 105 other of said pawls, a crank arm connected to said lever intermediate the ends thereof, and an actuating device operatively connected to said crank arms, whereby a movement of said actuating device in one direction 110 will cause said pawls to be simultaneously moved in opposite directions.

18. In a typewriting machine, the combination of two ribbon spools, a ratchet wheel for each spool, a driving pawl for each 115 ratchet wheel, a crank arm carrying one of said pawls, a lever fulcrumed at one end and carrying at the other end thereof the other of said pawls, a crank arm connected to said lever intermediate the ends thereof, an actuating bar which moves longitudinally and is operatively connected to said crank arms to move them and the parts controlled thereby, whereby a movement of said bar longitudinally in one direction will cause a simultaneous movement of the pawls in opposite directions, and means operative at each printing operation to shift said actuating bar longitudinally.

19. In a typewriting machine, the com-

- 5 combination of two ribbon spools, a ratchet wheel for each spool, a driving pawl for each ratchet wheel, a crank arm carrying one of said pawls, a lever fulcrumed at one 5 end and carrying at the other end thereof the other of said pawls, a crank arm connected to said lever intermediate the ends thereof, an actuating device operatively connected to said crank arms, whereby a movement of said actuating device in one direction will cause said pawls to be simultaneously moved in opposite directions, a reversing device associated with each of said pawls and adapted to maintain its pawl out of coöperation with the associated ratchet wheel, a ribbon guide associated with each ribbon spool and connected with the associated reversing device and operative to shift the same when a contact on the ribbon engages the associated ribbon guide, and intermediate connections between said reversing devices by which a movement of one reversing device to disengage its pawl will cause a movement of the other reversing device to enable the other pawl to engage its ratchet wheel. 60
- 10 20. In a typewriting machine, the combination of two ribbon spools, a ratchet wheel for each spool, a driving pawl for each ratchet wheel, a crank arm carrying one of said pawls, a lever fulcrumed at one end and carrying at the other end thereof the other of said pawls, a crank arm connected to 65 said lever intermediate the ends thereof, an actuating device operatively connected to said crank arms, whereby a movement of said actuating device in one direction will cause said pawls to be simultaneously moved in opposite directions, a reversing device associated with each of said pawls and adapted to maintain its pawl out of coöperation with the associated ratchet wheel, and automatically actuating means for controlling said reversing devices. 70
- 15 25. In a typewriting machine, the combination of two ribbon spools, a ratchet wheel for each spool, a driving pawl for each ratchet wheel, a crank arm carrying one of said pawls, a lever fulcrumed at one end and carrying at the other end thereof the other of said pawls, a crank arm connected to 75 said lever intermediate the ends thereof, an actuating device operatively connected to said crank arms, whereby a movement of said actuating device in one direction will cause said pawls to be simultaneously moved in opposite directions, a reversing device associated with each of said pawls and adapted to maintain its pawl out of coöperation with the associated ratchet wheel, and a ribbon guide associated with each ribbon 80 spool and connected with the associated reversing device and operative to shift the same when a contact on the ribbon engages the associated ribbon guide. 85
- 30 35. In a typewriting machine, the combination of two ribbon spools, a ratchet wheel for each spool, a driving pawl for each ratchet wheel, a crank arm carrying one of said pawls, a lever fulcrumed at one end and carrying at the other end thereof the other 90
- 40 45. In a typewriting machine, the combination of two ribbon spools, a ratchet wheel for each spool, a driving pawl for each ratchet wheel, a crank arm carrying one of said pawls, a lever fulcrumed at one end and carrying at the other end thereof the other 95

Witnesses:

E. S. BOYNTON,
W. W. BRAND.

ARTHUR J. BRIGGS.

Signed at Syracuse, in the county of Onondaga, and State of New York, this 19th day of November, A. D. 1913.

It is hereby certified that in Letters Patent No. 1,214,891, granted February 6, 1917, upon the application of Arthur J. Briggs, of Syracuse, New York, for an improvement in "Type-Writing-Machines," an error appears in the printed specification requiring correction as follows: Page 7, claim 5, strike out line 52 and insert the words *each printing operation, and ribbon spool*; and that the said Letters Patent should be read with this correction therein that the same may conform to the record of the case in the Patent Office.

Signed and sealed this 23d day of April, A. D., 1918.

[SEAL.]

F. W. H. CLAY,

Acting Commissioner of Patents.

Cl. 197-151.
